DESIGN FOR A COMPOUND TOOL

Ernest T. Frisk, Hibbing, Minn.

Application October 11, 1943, Serial No. 111,329

Term of patent 14 years

To all whom it may concern:

Be it known that I, Ernest T. Frisk, a citizen of the United States, residing at Hibbing, in the county of St. Louis and State of Minnesota, have invented a new, original, and ornamental Design for a Compound Tool, of which the following is a specification, reference being had to the accompanying drawing, forming part thereof.

In the drawing, the figure is a perspective view of a compound tool showing my new design.

I claim:

The ornamental design for a compound tool, as shown.

ERNEST T. FRISK.
